UNITED STATES PATENT OFFICE.

WILLIAM J. GRIFFITHS, JR., OF MOUNT VERNON, NEW YORK, ASSIGNOR TO ELECTRIC MAIL CARRIER COMPANY, OF NEW YORK, N. Y., A CORPORATION OF NEW YORK.

APPARATUS FOR DELIVERING MAIL.

1,157,981.

Specification of Letters Patent.

Patented Oct. 26, 1915.

Application filed March 25, 1912. Serial No. 686,184.

To all whom it may concern:

Be it known that I, WILLIAM J. GRIFFITHS, Jr., a citizen of the United States of America, and a resident of Mount Vernon, 5 Westchester county, New York, have invented certain new and useful Improvements in Apparatus for Delivering Mail, of which the following is a specification.

This invention relates to improvements in 10 mail delivery apparatus with particular reference to apparatus for delivering mail to the tenants on the different floors of apartment houses or other large buildings.

The object of the invention is to provide 15 means whereby mail or other matter may be automatically conveyed from a charging or starting station to predetermined delivery stations in the building and automatically discharged at these latter stations, together 20 with means or mechanism whereby the operations of the carrier are controlled automatically so that only a given carrier will discharge its contents at a given discharge or delivery station.

25 Other objects ancillary to the main object of the invention will appear later.

To this end the invention comprises such parts and elements as together are comprised in a mail delivery apparatus as hereinafter set forth while reference is had to the accompanying drawings in which—

Figure 1 is a front view, partly broken away, of a mail delivery apparatus embodying my invention. Fig. 2 is a central vertical section of Fig. 1. Fig. 3 is a view similar to Fig. 1 but with the front portion removed. Fig. 4 is a sectional view of Fig. 3. Fig. 5 is a side view of a mail carrier or box and also shows details of the mechanism 40 near the charging or starting station, parts being in section. Fig. 6 is a front view of Fig. 5. Fig. 7 is a top view of Fig. 6. Fig. 8 is a view showing a mail carrier in the position of discharging mail. Fig. 9 is a 45 diagram of the electrical controlling means, and Fig. 10 is a detail view of a signal apparatus.

Referring in general to the first four figures, which are largely diagrammatic in 50 character, the apparatus comprises a casing 1 hereinafter referred to as the shaft. The

shaft extends from the machinery floor of the building to whatever height is necessary in order to deliver mail to the top floor tenants and is for each floor provided with delivery boxes numbered 2 to 7 inclusive, there being one delivery box for each tenant. In the arrangement illustrated in the drawings and described hereinafter by way of example, it is supposed that the building contains 55 three floors with two tenants on each floor, but it will be understood that my invention is applicable to a building of any height and with any number of tenants on the floor. Each delivery box is provided with a door 8 60 which can be opened by key by the tenant whose mail is delivered in the particular box. On the machinery floor 9 there is provided a hoisting apparatus represented by the drum 10 operated by the motor 11. 65 From the one side of the drum a cable 12 passes up through the shaft to the top thereof, over a pulley 13 and the other end of said cable is attached to and supports the carrier frame 14. Another cable 15 passes 70 from the other side of the drum and up over pulley 16 to the counterweight 17 which balances the carrier frame and the carrier boxes. In this instance there are six carrier boxes 18, 19, 20, 21, 22 and 23 contained in 75 the frame 14. The boxes are arranged in vertical succession, but might be arranged in two or more rows if desired. Each box bears the name of a respective tenant in the vertical order of their location. On the first 80 floor, preferably, of the building the shaft is provided with an opening closed with a door 24. The latter is open and closed with a key by the person who delivers the mail to the tenants. In most, if not all cases, this person will be the regular letter carrier. That portion of the apparatus adjacent the door 85 24 will hereinafter be referred to as the charging or starting station 25, see Fig. 2. For the convenience of the letter carrier the 90 names of the tenants may be displayed on the inside of the door as shown.

Referring now to Figs. 5 to 8 it will be seen that the frame 14 is provided with fixed shelves 26 having several ridges 27 100 upon which rest the carrier boxes 28. I will describe but one carrier box, as they

are all alike. Each carrier box 28 is pivoted in the frame 14 on a shaft 29. The box is preferably square and provided with a lid 30 pivoted to the box on a pin 31. 5 The lid has a thumb piece 32 and covers the opening 33 through which mail is inserted in the box. The latter is provided with a bottom 34, see Fig. 8, which is pivoted to the box at 35. The bottom 34 rests on the aforesaid ridges 27. 36 is a stop which limits the fall of the bottom 34 when mail is being discharged, and 37 is a stop across the frame 14 to prevent the boxes from swinging too far to the rear after having discharged mail. On the shaft 29 is pivoted a catch 38 adapted to be engaged by a trip 39 fast on the pin 31 on which the lid is hinged. 40 is an ejector pivoted on the back of the box at 41 and which is held in 15 its normal position by gravity as shown in Fig. 5. The pin 31 extends through a slot 42 in the frame 14 which slot is shown near the top of Fig. 5 only for the sake of clearness, and outside the frame the pin carries 20 a spring contact 43 adapted to bridge between two bars or contacts 44 which extend the full length of the charging station, 25 Fig. 5.

The frame 14 is provided with suitable 30 shoes 45 which engage guides 46 in the shaft 1. In the latter is fixed a cam 47 opposite each delivery box, Figs. 1 and 2. These cams are spaced or offset horizontally in the shaft so that only one of them will 35 engage a particular ejector 40 to operate a particular box, and of course the ejectors 40 are spaced or offset correspondingly, as will be understood. For example, cam 47 opposite box 2 will operate, say, carrier box 40 23 and cam 47 opposite box 3 will operate carrier box 22 and so forth. The order in which the boxes are operated to discharge mail is of course immaterial.

Whenever possible and convenient the 45 door 24 will be so large that all the carrier boxes are in view at the same time when the door is opened. This will not always be practicable however, and in the drawings I have illustrated a proposition in which 50 only half the total number of carrier boxes are visible through the door at one time.

Near the charging station 25 there is provided a three point snap switch 50 having a fingered wheel 51 adapted to be rotated by the cams 48 carried by the lowermost carrier box as will hereinafter appear. Inside the door there is located an operating 55 four point snap switch 52, which is the starting switch used by the person delivering 60 the mail.

Referring now to the diagram in Fig. 9 it will be seen that the switches 50 and 52 are interconnected by the wires 53 and 54. 55 is a cut off switch connected to switch

52 by wires 56 and 57. The switch 55 is operated by a solenoid for actuating a core which latter releases a brake on the hoisting drum 10. 60 is the field of the motor 11. 61 is a reversing switch operated by a solenoid 62, and having three contact blades 63, 64 and 65. 66 is a screw which rotates with the hoisting drum 10 and upon which travels a nut 67 having a contact blade 68 insulated therefrom and adapted to make contact with the contacts 69 and 70. The 75 traveling contact 68 and contacts 69 and 70 form a limiting switch for limiting the travel of the carriers in the shaft. The blade 68 is connected by flexible cable 71 and wire 72 to the solenoid 62 and switch 55, and is 80 also connected to the right side of reversing switch 61 at contact 73. Contact 70 is connected to the left side of the reversing switch by wire 74. Both contacts 69 and 70 are connected to the bars 44 which are 85 of a length equal to the height of a section of carrier boxes. 75, 76 are the electric mains.

The operation is as follows: Normally the carrier boxes are in the position shown in Fig. 2, that is the uppermost section of boxes is directly inside the door 24 and in full view of the letter carrier. The door is opened and mail, if any, deposited in the first three boxes. Then the operating switch 52 is pushed and the current passes from 75, through switch 50, wire 54, switch 52, wire 56, switch 55, solenoid 59 (releasing the brake), field 60, blade 63, through the motor 11, blade 64, wire 74, contact 70 and 100 out through main 76. Consequently the motor begins to rotate the hoisting drum and the carrier boxes ascend until the switch cams 48 engage the wheel 51 on the switch 50, throwing the latter to the right 105 in Fig. 9 which cuts off the current from the motor and also sets the brake and the second section of boxes stops in position to be charged. The brake is not shown as it is a matter of common knowledge to those skilled in the art to apply a band brake to a drum and operate the band by the plunger of a solenoid. Next the second section of boxes are charged with mail, the operating switch 52 is operated again and now the current passes by way of 75, 50, 53, 52, 56, 55, 59 and out as before through 76. This again starts the motor and now the carrier boxes ascend to the top of the shaft 1. At the same time, however, the nut 67 is moved to 110 the left on shaft 66 and the parts are so timed, that when the frame 14 has reached the top of the shaft, the blade 68 on the nut 67 contacts with contact screw 70. This has the effect of throwing the solenoid 62 into the circuit and the current passing from switch 55 through 72, solenoid 62 and out through 71, 70 and 76. When the sole-

noid 62 is energized, it pulls up the core and the blades 63, 64, 65 and now the current passes from 59 to 60, blade 64, through the armature in reverse direction, blade 63 and 5 out thus reversing the rotation of drum 10 and the frame 14 with the boxes descends in the shaft. The nut 67 now moves to the right while the solenoid 62 remains energized, and when the blade 68 contacts with 10 69 the current passes from switch 55 through wire 77 to 69 and through 68, 71, 73, 65 and out through 74, 70 and 76. This flow of the current energizes solenoid 58 which then breaks the connection in switch 15 55 and the motor ceases to operate. The reversing switch drops and the circuit is ready for another operation.

The bars 44 will be bridged by the contact 43 every time the lid is lifted on a box 20 to insert mail or in case a lid should remain open by mail projecting from the box. While this condition exists the carrier boxes remain stalled because the bridging of contact 44 energizes solenoid 58 which breaks 25 the connection at 55 whenever switch 52 is operated, and by this means the carrier boxes are prevented from ascending until the mail has been properly inserted in the boxes.

30 Another feature should be noted. When the boxes descend the ejectors 40 will of course abut their respective cams 47 which will lift the ejector and swing it in under the catch 38 as seen in dotted lines in Fig. 5. 35 And the ejector will not be released except as the lid is lifted when the trip 39 hits the catch to release the ejector, and this is only done when there is mail to be inserted in the particular box. Hence, when there 40 is no mail the ejector remains up and that particular box is not swung into discharge position as in Fig. 8.

In Fig. 10 I have shown a signaling device to advise the tenant that mail is being 45 discharged into his delivery box. 80 is a contact pivoted at 81 in the delivery box. When mail is being discharged, the contact 80 is brought into contact with a spring contact 82 and a local circuit closed to ring a bell or other signaling device 83.

The foregoing is thought to clearly set forth the construction and operation of the apparatus. Various changes in the detailed construction may be made without departing 55 from the principle of the invention, but I claim all such changes as properly come within the scope of the invention and the appended claims.

I claim:

60 1. The combination of a shaft, individual carriers adapted to receive mail or similar matter, means for operating the carriers in said shaft and mechanism for operating only the loaded carriers into discharging

positions at predetermined points in said shaft.

2. The combination of a shaft, carriers adapted to receive mail or similar matter, ejectors carried by said carriers, selective means in said shaft adapted to coöperate 70 with the said ejectors at selected points in the shaft to discharge the said carriers and means on the latter for keeping the ejectors inactive on the carriers which do not contain any mail.

75 3. The combination of a shaft, a plurality of mail carriers within said shaft, means for operating said carriers stepwise to load the same and for operating said carriers continuously the length of said shaft to discharge the mail, said means comprising electric motive power including an electric circuit, a manually operated switch for closing the circuit to operate the carriers stepwise, means for automatically opening said 80 circuit after the stepwise movement of the carriers has been completed and means controlled by said manually operated switch for causing said carriers to travel the length of the said shaft.

90 4. The combination of a shaft, a plurality of mail carriers within said shaft, means for operating said carriers stepwise to load the same and for operating said carriers continuously the length of said shaft to discharge the mail, said means comprising electric motive power including an electric circuit, a manually operated switch for closing the circuit to operate the carriers stepwise, means for automatically opening said 85 circuit after the stepwise movement of the carriers has been completed, means controlled by said manually operated switch for causing said carriers to travel the length of the said shaft, and a reversing switch for automatically reversing the current in said circuit to cause said carriers to return to starting position.

95 5. The combination of a shaft a portion of which forms a starting station, a plurality of individual interconnected carriers adapted to be loaded with mail at said starting station, an electric circuit and electrically operated means for operating said carriers lengthwise in the said shaft, a pair 110 of fixed contact members in the latter at the said starting station and connected to the said electric circuit and means carried by each of said carriers and adapted to bridge the said contact members to short 115 circuit, the said electric circuit, while any one of the said carriers is being loaded.

120 6. The combination of a shaft, a plurality of mail carriers adapted to be loaded with mail at a given point in said shaft, an electric circuit for operating said carriers within the latter, a pair of fixed contacts in said circuit supported in said shaft at said given

point, a movable contact member supported on each of said carriers and means for automatically operating said movable contact member to contact with the said pair of fixed contacts for short circuiting the said electric circuit while any one of the said carriers is being loaded.

Signed at New York, N. Y. this 23' day of March 1912.

WILLIAM J. GRIFFITHS, JR.
